DESIGN FOR A LADY'S HAND BAG

Julian Brenner, New York, N. Y.

Application September 5, 1934, Serial No. 53,203

Term of patent 3½ years

To all whom it may concern:

Be it known that I, Julian Brenner, a citizen of the United States of America, residing in Manhattan, county of New York, and State of New York, have invented the new, original, and ornamental Design for a Lady's Handbag, of which the following is a specification, reference being had to the accompanying drawing, forming part thereof, wherein,

I claim:

The ornamental design for a lady's handbag, substantially as shown.

JULIAN BRENNER.
